UNITED STATES PATENT OFFICE

172,978

ELECTRIC ROAD FLARE

Robert F. McGrath, Alliance, Frank E. Scott, Canfield, and Joel E. Sames, Galion, Ohio, assignors, by direct and mesne assignments, of one-half to said Sames and one-half to Buffalo Weaving and Belting Company, Alliance, Ohio, a corporation of New York

Application March 26, 1954, Serial No. 29,706

Term of patent 14 years

(Cl. D72—1)

To all whom it may concern:

Be it known that we, Robert F. McGrath, Frank E. Scott, and Joel E. Sames, all citizens of the United States, residing, respectively, at Alliance, Stark County, Ohio; Canfield, Mahoning County, Ohio; and Galion, Crawford County, Ohio, have invented a new, original, and ornamental Design for an Electric Road Flare, of which the following is a specification, reference being had to the accompanying drawing, forming a part hereof.

Fig. 1 is a perspective view of an electric road flare, showing our new design;

Fig. 2 is a side elevation of the electric road flare shown in Fig. 1; and

Fig. 3 a top plan view of the electric road flare shown in Fig. 1.

We claim:

The ornamental design for an electric road flare, substantially as shown.
